MAGAZINE-PENCIL CLIP.

Application filed August 20, 1921. Serial No. 493,884.

This invention relates to magazine pencils of the clutch type and an object of the invention is to provide a pencil in which the lead will be firmly held in position during use.

Another object of this invention is to provide a pencil as specified wherein an attractive appearing pencil is provided by the use of hard rubber, fibre, or analogous materials in contrast with precious metals, and further to provide a reinforcing sleeve to prevent breakage, warping, or distorting of the sleeve which is constructed of rubber, fibre or analogous material.

15 A further object of the invention is to provide a novel manner of attaching a clip to the pencil body.

The present application embodies improvements over our clutch pencil disclosed in the application filed October 2, 1920, Serial No. 414,165.

Other objects of the invention will appear in the following detailed description and in the accompanying drawing wherein:

25 Fig. 1 is a longitudinal section through the improved pencil.

Fig. 2 is a longitudinal fragmentary view of the casing of the pencil.

30 Fig. 3 is an enlarged fragmentary view of the outlet end of the lead guiding sleeve.

Fig. 4 is an enlarged fragmentary section of the tip of the pencil.

Fig. 5 is an enlarged fragmentary side elevation of the casing-reinforcing sleeve.

35 Fig. 6 is a fragmentary side elevation of the pencil.

Fig. 7 is a cross section on the line 7—7 of Fig. 1.

40 Fig. 8 is a cross section on the line 8—8 of Fig. 1.

Fig. 9 is a detail view showing a panel attaching plate embodied in the pencil structure.

45 Referring more particularly to the drawing the improved pencil comprises a body shell structure 1 which is composed of an inner sleeve 2 of metal and an outer sleeve 3 of rubber, celluloid, fibre, or analogous material, which is mounted over the metal

50 sleeve 2 and engages, at its butt end, against the annular shoulder 4 formed on the metal sleeve 2. The sleeve 3 is provided to add attractiveness to the appearance of the pencil and eliminate the liability of chipping,

cracking, or uneven coloring of the surfaces which is caused by enamelling a pencil wherein any desired color, preferably black, may be utilized for the main body of the pencil while the tip 5 and cap 6 are formed of sterling silver, gold or other precious metals, which in combination with the black or colored sleeve 3, provides an attractive appearing pencil.

The sleeve 3 has its tip end reduced in diameter and tapered as shown at 7 and the base flange 8 of the tip 5 fits over the reduced end as clearly shown in Fig. 1 of the drawing. The metal sleeve 2 is internally screw threaded at its tip end as shown at 9 for threadable connection with the connecting sleeve 10 which is carried by the lead guiding sleeve 11 and serves to connect the body shell 1 and tip 5 as more specifically described in our companion application filed October 2, 1920, Serial No. 414,165. The walls of the tip 5 gradually increase in thickness towards the apex thereof as clearly shown in Fig. 4 of the drawing so that when the tip is drilled to provide the lead receiving bore or opening 5' the said opening will be provided with parallel sides for a comparatively long distance preventing the formation of sharp edges which cut into the lead during use and increase the liability of breaking of the lead.

85 The tip 5 is split longitudinally from its apex as shown at 12 and the split is constricted towards the apex or point of the tip as clearly shown in Fig. 4 of the drawing for securely gripping a lead and holding it in place. To provide a firmer and more secure grip on the lead the tip end 13 of the sleeve 11 is also split longitudinally as shown at 14 providing a dual grip for the lead. As clearly shown in Fig. 3 of the drawing the tip end 13 of the sleeve 11 is constricted by swaging inwardly, which swaging forms a relatively long bore 11' of substantially uniform diameter, to provide the proper gripping engagement with the lead. It is well known that after continuous use, pencils of this type become worn or separated so that a firm and secure grip upon the lead cannot be had and it is to overcome this separating and loosening of the grip of the pencil upon the lead that the dual gripping action of the tips 13 and 5 is provided. The lead 15 is fed out of the

tip 5 by the mechanism generically shown at 16, which mechanism is more specifically described in the previously mentioned application. The sleeve 11 and ears 17 cut thereon at its end adjacent the butt end of the pencil which ears are bent laterally providing a plurality of spaces 18 for receiving leads to be used in the pencil and consequently forming a lead magazine in the pencil. The ears 17 on the tube or sleeve 11 also act to centralize said sleeve in the reinforcing body sleeve 2.

A novel manner of attaching the clip 20 to the pencil is provided. The metal sleeve 2 is provided with an oval opening 21 therein and with an inwardly struck strap 22 formed directly above the opening 21 and free at its upper and lower edges. The strap 22 is forced inwardly as clearly shown in Figures 2 and 8 of the drawing and the attaching portion 23 of the clip 20 is inserted through an arcuate slot 24 formed in the sleeve 3 and extends upwardly in facial abutment with the inner surface of the metal sleeve 2, being forced beneath the strap 22 and having its free end projecting behind the strap, thereby providing an easily assembled neat appearing manner of attaching the clip to the pencil which, owing to the substantial transverse curvature 25 in the clip, which curved portion extends through the openings 21 and 24, will securely hold the clip against accidental movement of the pencil and provide a secure permanent connection between the clip and pencil.

By referring to Fig. 2 it will be noted that the slot 24 is smaller than the opening 21 so that when the slot 24 is at the bottom 40 of the opening, the attaching portion 23 will lie in a position to move under the strap 22 when the tubes 2 and 3 are slid relative to one another. Thus it will be seen that automatically in the relative movement of the tubes the clip is secured in place.

The sleeve 2 is externally threaded as shown at 27 outwardly of the shoulder 4 and it receives the connecting collar 28 which serves to connect the eraser carrying head 29 to the body of the pencil so as to permit rotation of the said head for feeding the lead 15 out of the pencil or to permit the receding of the lead feeding means into the pencil.

A rivet 30 extends through the attaching portion 23 of the clip 20, through the sleeve 3 and through the strap 22 serving to attach a plate 31 to the outer surface of the body 1 of the pencil. The edges of the plate 31 are beveled as clearly shown in Fig. 8 of the drawing for snugly fitting in the bevel edged recess in a monogram or indicia panel such as described in our co-pending application filed October 9, 1920 65 Serial No. 415,728. The plate 31 is split

longitudinally as shown at 32 so that its width may be varied slightly to compensate for slight variations in recesses in indicia panels.

Having thus described our invention what we claim is:

1. In a pencil, a body shell comprising a tube, said tube provided with an opening, a strap struck inwardly into the tube, and a clip having an attaching portion inserted through the opening in the tube and between the tube and said strap.

2. In a pencil, a body shell comprising a tube, said tube provided with an opening, a strap struck inwardly into the tube, and a clip having an attaching portion inserted through the opening in the tube and between the tube and said strap, and means rigidly connecting said attaching portion to said strap.

3. In a pencil, a body shell comprising a tube provided with an opening, a strap struck from said tube, a panel retaining plate against the outer surface of said body shell, a clip, an attaching portion on said clip inserted through said opening and between the strap and tube, and a fastener extending through said plate, attaching portion and strap.

4. In a pencil, a body shell, comprising a sleeve of hard rubber, a reinforcing metal tube within said sleeve, said sleeve and tube provided with registering transverse openings, a strap struck from said tube, a clip, an attaching portion on said clip inserted through said openings and behind said strap, and fastening means connecting said strap and attaching portion.

5. A pencil including a sleeve provided with a transverse opening, a tube mounted within the sleeve and provided with a transverse opening in registration with the transverse opening of the sleeve, a strap struck from the tube, and a clip having an attaching portion inserted through the openings behind the strap.

6. In a pencil, a body shell, comprising a sleeve of hard rubber, a reinforcing metal tube within said sleeve, said sleeve and tube provided with registering transverse openings, a strap struck from said tube, a clip, an attaching portion on said clip inserted through said openings and behind said strap, a panel retaining plate positioned against the outer surface of said hard rubber sleeve, and a fastening device extending through said plate, said tube attaching portion and strap.

7. In a pencil, a body shell comprising an outer decorative sleeve, an inner tube, said outer decorative sleeve provided with a transverse opening, a strap struck inwardly from said tube, said tube provided with a longitudinal opening in alignment with said strap, a clip having an attaching portion,

the attaching portion of said clip inserted through said transverse opening and behind said strap.

8. In combination with a body having an opening formed therein, a clip having a portion extending through the opening with a portion extending along the exterior surface of the body downwardly of the opening and another portion extending along the interior surface of the body upwardly of the opening, and means for securing the last mentioned portion directly to the body.

9. In combination with a pair of concentrically arranged tubes, a clip having an attaching portion passing through both tubes and secured to the inner surface of one of the tubes and attaching means between both tubes and the clip.

10. In combination with a pair of tubular members capable of relative movement, one of the members being provided with a struck out portion, a clip having a portion confined between the struck out portion and the adjacent walls of said one member automatically secured to both tubes in the relative movement thereof.

11. In combination a pair of slidable tubes, one provided with a strap, a clip having a portion passed through both tubes and moving into securing engagement with the strap in the relative movement of the tubes in a predetermined direction.

In testimony whereof we affix our signatures.
